UNITED STATES PATENT OFFICE

102,761

DESIGN FOR AN ASHTRAY OR SIMILAR ARTICLE

Robert A. May, Washington, Pa., assignor to Duncan & Miller Glass Company, Washington,
Pa., a corporation of Pennsylvania

Application November 16, 1936, Serial No. 65,946

Term of patent 3½ years

To all whom it may concern:

Be it known that I, Robert A. May, a citizen of the United States, residing at Washington, Pennsylvania, have invented a new, original, and ornamental Design for an Ashtray or Similar Article, of which the following is a specification, reference being had to the accompanying drawing, forming a part thereof.

In the drawing:

Figure 1 is a plan view of an ashtray showing
my new design;

Figure 2 is a side elevation of the ashtray

Figure 3 is a front elevation of the ashtray shown in Figures 1 and 2.

I claim:

The ornamental design for an ashtray or similar article substantially as shown.

ROBERT A. MAY.
